UNITED STATES PATENT OFFICE.

ADOLPH AUGUST ADAMS, OF PHILADELPHIA, PENNSYLVANIA.

WINDMILL.

Application filed May 17, 1927. Serial No. 131,970.

My invention relates to windmills and more particularly to the type of windmill having a rotatable cylindrical structure enclosed by a stationary cylindrical structure.

5 I am aware that windmills of this type have heretofore been produced but, to the best of my knowledge, none of such windmills have been successful or have been capable of producing a relatively large amount of power, 10 and the principal object of my invention is to provide a windmill which overcomes the objectionable features of those heretofore produced and which is capable of generating a large amount of power relatively to its size. 15 Another object of my invention is to provide a windmill so designed that several independent structures may be erected one above the other and thus be capable of producing a greater amount of power and utilizing the 20 higher air currents.

These objects, and other advantageous ends which will appear hereinafter, I attain in the following manner, reference being had to the accompanying drawings in which

25 Figure 1 is a top plan view of a windmill embodying my invention,

Figure 2 a central vertical sectional view showing two of the windmills illustrated in Figure 1 erected one above the other, and

30 Figure 3 a sectional plan view taken substantially on line 3—3 on Figure 2.

Referring now more in detail to the drawings, the outer stationary cylinder 5 is composed of an upper ring 6, a lower ring 7 and a plurality of vanes 8 secured between rings 6 and 7 and disposed at an angle of approximately 45° to the radii of cylinder 5. An inner cylinder 9 is composed of an upper ring 10, a lower ring 11 and a plurality of vanes 12 secured between rings 10 and 11 and disposed at an angle of approximately 30° to the radii of cylinder 9.

Cylinder 5 may be erected on any suitable structure and is preferably securely braced 45 so that it may withstand the onslaught of high winds. Cylinder 9 is rotatably mounted within cylinder 5 and it is preferably of such size that a very small clearance is provided between its outside and the inside of cylinder 5. Cylinder 9 may be pivoted on a central shaft or otherwise as is customary in mounting such cylinders or it may be provided with a track 13 which I have shown as being of channel cross-section and having one 50 flange secured to the inner edges of vanes 12

while its other flange is adapted to engage grooved rollers 14 secured to shafts 15 rotatably mounted in bearings 16.

When but a single set of cylinders is employed, bearings 16 may be mounted on the 60 top of the structure which carries the windmill while, if more than a single set of cylinders is employed, the upper bearings 16 may be mounted on braces 17 secured between two cylinders 5 and extending across cylinders 9 65 but not coming into contact therewith. Any number of rollers 14 may be employed but I find in practice that three is the most efficient number and consequently I have shown brace 17 as having three legs or parts extending 70 radially from the center of the structure.

Power created by the rotation of cylinder 9 may be transmitted by means of a central shaft 18 which is rotatably mounted in a bearing 19 secured to a brace 20 extending across 75 the top of cylinder 5 but spaced from cylinder 9. When more than one set of cylinders are employed, I provide a bearing 21 in the center of brace 17 through which shaft 18 extends. Rotation is imparted to shaft 18 80 by means of a strut 22 having its ends secured to upper ring 10 and carrying a collar 23 which is fixed to shaft 18. A second strut 24 may have its ends secured to track 13 and its center secured to the shaft by means of a 85 second collar 23a when so desired. The lower end of shaft 18 may be connected to a generator 25, either directly or through a series of gears, and the generator mounted on the structure supporting cylinder 5 or at any 90 other convenient place.

Where two or more sets of cylinders are erected one above the other and shaft 18 is connected directly to the armature shaft of generator 25, I preferably provide an anti-friction bearing 26 between the top of bearing 21 and a collar 27 fixed to shaft 18 in order to relieve generator 25 from the weight of shaft 18. Also, it is evident that power generated by the rotation of cylinder 9 may 95 be utilized by making mechanical connection to shaft 18.

Small generators may be connected to shafts 15 and rotated by the action of track 13 engaging rollers 14. When this method 100 is employed, the interior bracing may be omitted and a structure built up inside of the several tiers or sets of cylinders and be adapted to support the load thereof and to rigidly hold same against swaying.

By referring to Figure 3 it will be noted that, on the same radial line, the outer end of each vane 8 overlaps the inner end of the adjacent vane. Assuming that the wind is blowing in the direction indicated by arrows 28, 29 and 30, it cannot blow directly into the cylinders but is deflected by vanes 8 so that it strikes vanes 12 at an angle and causes cylinder 9 to rotate in a clockwise direction.

10 The wind will strike the vanes at the right of arrow 28 at increasingly greater angles, relatively to the direction of the wind, until it strikes the vane ahead of arrow 29 at a right angle. To the right of arrow 29, the 15 wind is spilled around the side of cylinder 5 and creates a partial vacuum under its lee.

To the left of arrow 28, vanes 8 are disposed at sharper angles to the direction of the wind until the vane at the right of arrow 30 is 20 nearly parallel thereto, thus providing one opening that is nearly free for the ingress of the wind, but at this point the vane on cylinder 9 is disposed at substantially the correct angle to the path of the wind to derive 25 the greatest amount of power therefrom. To the left of arrow 30, vanes 8 slope in the opposite direction, relatively to the direction of the wind, at increasingly greater angles so as to direct the wind against vanes 12 at 30 substantially the correct angle.

From the foregoing and with further reference to Figure 3, it will be noted that vanes 8 are so disposed that, of the half-circumference of cylinder 5 presented to the wind, 35 about three-fourths of same is sealed against direct entry by the wind and approximately one-fourth partially open to the entry of the wind. In this manner, a great amount of power is taken from the wind and thus a 40 higher vacuum is created under the lee of cylinder 5 than is ordinarily obtained with windmills of this type.

After the air has passed between vanes 8 and caused cylinder 9 to rotate by coming in 45 contact with vanes 12, as above described, it is drawn outwardly by the action of the vacuum area and gives vanes 12 a second impulse while passing between them. In passing through cylinder 9, I find that the 50 air moves in a circular path, as indicated by

the arrow 31, and thus meets vanes 12 at a sharp angle in passing from the cylinder.

While I have described my invention as taking a particular form, it will be understood that modifications may be made without departing from the spirit thereof, and hence I do not limit myself to the precise construction set forth, but consider that I am at liberty to make such changes and alterations as fairly come within the scope of the appended claims.

I claim:

1. In a windmill having a stationary outer cylinder and a revoluble inner cylinder within the stationary cylinder, means for 65 revolvably supporting the inner cylinder including a track secured to the inside of the inner cylinder and rollers supported by a fixed part of the structure and engaging the track.

2. In a windmill having a stationary outer cylinder, a revoluble inner cylinder within the stationary cylinder and vanes forming the side walls of both cylinders, means for 75 revolvably supporting the inner cylinder including a channel shaped track secured to the vanes of the inner cylinder and rollers supported by a fixed part of the structure and engaging the track.

3. A windmill including a stationary cylinder adapted to be mounted upon a support and comprising an upper ring, a lower ring and vanes connecting the rings, an inner cylinder comprising an upper ring, a lower ring and a plurality of vanes connecting said 85 rings; an annular channel-shaped track secured to the inner edges of the vanes of the inner cylinder; bearings on the support; grooved rollers rotatable in the bearings and supporting one flange of the track; a brace 90 extending across the upper ring of the outer cylinder; a bearing on the brace; a vertical shaft rotatable in the bearing; a brace extending across the upper ring of the inner cylinder and fixed to the shaft; and a brace 95 extending across the track and fixed to the shaft.

In testimony whereof I have signed my name to this specification.

ADOLPH AUGUST ADAMS.
